UNITED STATES PATENT OFFICE.

JAMES C. DAWSON, OF ST. LOUIS, MISSOURI, ASSIGNOR TO SIEBER & TRUSSELL MNFG. CO., A CORPORATION OF MISSOURI.

LOOSE-LEAF BINDER.

No. 841,125.

Specification of Letters Patent.

Patented Jan. 15, 1907.

Application filed July 16, 1906. Serial No. 326,382.

To all whom it may concern:

Be it known that I, JAMES C. DAWSON, a citizen of the United States, and a resident of the city of St. Louis, State of Missouri, have invented certain new and useful Improvements in Loose-Leaf Binders, of which the following is a specification and which are illustrated in the accompanying drawings, forming a part thereof.

10 The invention relates to that class of loose-leaf binders in which there is provided a pair of cover-boards flexibly attached to a back member, this back member carrying arches, usually in ring form, upon which the leaves 15 to be bound together are secured.

The invention relates directly to the stiff fly-sheet or follower used in devices of this kind for facilitating the movement of the leaves upon the arches as the book is closed, 20 its object being to provide a fly or follower in a book of this character which will slide freely on the arches and will prevent the mutilation of the sheets.

Flies or followers of this character heretofore used have been provided either with a 25 round or oblong aperture for receiving the arch. The oblong form of aperture provides for a more free movement of the follower, but permits the mutilation of the sheets.

30 The invention consists in the device as hereinafter described and as illustrated in the accompanying drawings, in which—

Figure 1 is a full view of the inner face of the improved follower. Fig. 2 is a section of the follower on the line 2 2 of Fig. 1. Fig. 3 is a sectional view of the binder, taken on this line 2 2 of Fig. 1, through the follower. Fig. 4 is a detail sectional view of the binder, showing a modified form of follower. Fig. 5 40 is a detail face view of the form of follower shown in Fig. 4. Fig. 6 is a transverse section of the follower, a detail of one of the arches of the binder being shown, this figure being drawn on an enlarged scale. Fig. 7 is 45 a detail of a sheet used in a binder of this form, and Figs. 8 and 9 show a further modification.

The binder comprises the side plates 10 11 and the back-section 12, to which the side 50 plates are hinged. A plurality of arches 13 (only one of which is shown) are carried by the back member 12 in any suitable manner. The sheets 14 to be bound together are per-

forated, as shown at 15, to receive and slide upon the arches.

It has been found in practice that unless a stiff fly or follower is mounted with the sheets they are apt to bind on the arches as the back is closed, the side plate swinging as it does about a different center from that 60 on which the leaves turn. To obviate this difficulty, a stiff fly-sheet has been mounted on the arches between the leaves and the cover, and in order to facilitate the movement of such a follower upon the arch its 65 apertures have been made oblong, the longer diameter being upon the radius of the arch. Such an aperture, however, does not afford proper support for the limp sheets adjacent their perforations, and the binding of these 70 sheets upon the arch causes them to tear, as indicated at 16, upwardly from their apertures. This difficulty I have overcome by making the follower of two thicknesses of material, as shown at 17 18, and binding 75 them together, as by means of rivets 19. Each of the plates 17 18 is provided with oblong apertures for receiving the arches, as shown at 20 21, these apertures, however, being offset radially as to the arch to such an 80 extent that the opening for the arch is substantially circular, being bounded by the inner end of one aperture, as 20, and by the outer end of the other aperture, as 21. As the follower when thus made is advanced in 85 closing the book its points of contact 22 23 with the arch are further removed from parallelism with the arch than would be true were the follower of a single thickness and provided with a circular aperture of the same 90 size as that obtained in the manner described, and hence the tendency to bind upon the arch is greatly lessened.

The advantages of the circular aperture in that a better support is provided for the 95 limp leaves is, however, secured. The follower will slide as freely along the arch as if the aperture were oval and as effectually protects them from injury as if the aperture were round and formed in a single sheet or 100 plate.

The same result is secured in the modified form of construction illustrated in Figs. 4 and 5, wherein a follower 24 of a single thickness is shown and is provided with a round aperture 25, which, however, extends obliquely

through the plate, the latter being made of material of greater thickness than when the two plates are employed. I do not regard this form of construction, however, as desirable as that illustrated in Figs. 1, 2, 3, and 6, as it provides knife-edges for the aperture, and these edges are liable to become worn or broken.

A still further modification is shown in Figs. 8 and 9, in which the same action is obtained by a slightly different form of construction. The aperture in this instance is round; but the board is depressed immediately above the aperture, as shown at 26, and is raised immediately below the aperture, as shown at 27, thereby offsetting the lower and upper sides of the aperture and bringing the point of contact 22 and 23 substantially into line, as in the case of the form of construction shown in Figs. 1, 2, 3, and 6.

The several forms are generically alike in that the axis of the aperture in each instance is oblique to the plane of the plate.

I claim as my invention—

25 1. A stiff follower for loose-leaf books hav-

ing an arch-receiving aperture whose axis is oblique to the surface of the follower.

2. In a follower for loose-leaf books, in combination, a plurality of plates secured together, and each having an oblong arch-receiving aperture the major diameter of which is radial to the arch, the apertures of adjacent plates being longitudinally offset.

3. In a follower for loose-leaf books, in combination, a pair of stiff plates secured together, each plate having oblong arch-receiving apertures having their major diameters radial as to the arch, coöperating apertures of the two plates being longitudinally offset.

4. In a follower for loose-leaf books, in combination, a pair of plates secured together, each plate having arch-receiving apertures, coöperating apertures of the two plates being offset radially as to the arches.
